Finance Corporation, a Federal corporation

Application April 21, 1933, Serial No. 667,155

14 Claims. (Cl. 34—12)

In the manufacture of plywood wherein the various plies are united with a synthetic resin adhesive, it is advantageous to apply the adhesive in a liquid state and then to dry the adhesive. It is desirable that the drying be done both effectively and quickly. The object of the present invention is to produce a simple and novel machine for thus drying glue sized sheets of veneer and the like.

10 The various features of novelty whereby my invention is characterized will hereinafter be pointed out with particularity in the claims; but for a full understanding of my invention and of its objects and advantages, reference may be had to the following detailed description taken in connection with the accompanying drawings, wherein:

Figure 1 is a top plan view of the machine embodying the present invention; Fig. 2 is a side elevation of the machine, on a larger scale, only the two end portions being shown; Fig. 3 is an end view of the machine, on the same scale as Fig. 2, the middle portion being omitted; Fig. 4 is a vertical transverse section, on a greatly enlarged scale, showing a fragment of the machine; Fig. 5 is a longitudinal vertical section, on the same scale as Fig. 4, through the inlet end of the machine, only a fragment being shown; and Fig. 6 is a section on line 6—6 of Fig. 5.

20 The principle of my invention consists in the carrying of the sheet to be dried through a drying chamber where it is exposed to drying currents of air or other suitable fluids; the sheets being supported in such a manner that the drying fluids have free access to substantially the entire surface area on both sides or faces of each sheet, and the currents of drying fluids being so directed that the sheets will be carried along in substantially the same way as though they were 25 passing through still air.

The sheets to be dried can most conveniently be carried through the drying chamber while lying on an endless conveyor. I have therefore provided a large box-like casing or housing 1 30 closed at the top and at the sides and being sufficiently open at the ends to permit veneers or the like to be placed into the machine and removed therefrom. Within this casing or chamber is a long, wide, endless conveyor, at least 35 the upper run of which is horizontal. This conveyor, as best shown in Figs. 4, 5 and 6, is composed of two parallel endless chains 2 and 3 spaced apart the width of the machine and connected together at intervals by cross bars 4 which, in the arrangement shown, are angle

5 irons. The angle irons are arranged outwardly with respect to the chains. The bars 4 project laterally beyond the chains, resting at their ends upon tracks or rails 5 and 6, at least throughout the length of the upper run of the conveyor. The space between the two chains is also spanned by means that gives to the conveyor the effect of being a broad belt or band. In the arrangement shown, there is an angle bar 4 connected to every other link of each of the chains; each angle bar 10 being welded to a plate 7 as wide as the length of a link and extending from one chain to the other. Welded or otherwise secured to each of the plates 7 is the marginal portion of another plate 8 which also extends across the entire width of the conveyor and is wide enough to bridge the gap between the plate 7 to which it is secured and the next adjacent plate 7. This arrangement permits the conveyor to travel around suitable driving wheels 9. The chains and their driving 20 and supporting wheels may be of any usual or suitable type. In the arrangement shown, the part of each wheel that engages with its chain is octagonal in shape, each side of the octagon being equal to the length of one of the links of 25 the chain.

The veneers, sheets of which are indicated at A, do not rest directly on the conveyor but upon the upper edges of thin partitions or vanes 10 welded to the angle bars and held thereby in 30 such positions that they stand at right angles to the face of the conveyor. These vanes are not only parallel with each other, but they are of uniform height so that the upper edges of 35 the vanes along the upper run of the conveyor lie in the same horizontal plane.

The front end of the casing or housing has therein an opening 11 just above the front end of the conveyor, through which opening the veneers are inserted. The conveyor, driven as will 40 be hereinafter described, carries the veneer through the casing or housing to the opposite end where the veneer is discharged through an opening 12.

While traveling through the casing or housing 45 the veneer is subjected to currents of heated air forced through the interior of the casing or housing in the general direction of the length of the vanes on the conveyor. This air passes both above and below the veneers and, where the velocity thereof is sufficient for satisfactory drying, the air will blow the veneer off the conveyor toward one side of the casing. Therefore, although the vanes on the conveyor form, as it were, troughs through which warm air may flow 50 55

in contact with the under faces of the veneers, while other air may flow across the upper faces of the veneers, means must be provided to keep the veneers from being blown away. I have found that the most satisfactory means for this purpose is a second endless belt-like device above and similar to the conveyor. The upper endless member consists of chains 13 and 14, similar to the chains 2 and 3, having associated therewith angle bars 15, plates 16 and 17, and vanes 18, similar to the angle bars 4, the plates 7 and 8, and the vanes 10 of the carrier proper. The ends of the angle bars 15 project laterally beyond the chains, those along the lower run of the device 15 riding on stationary rails 19 and 20, directly above the rails 5 and 6, so that the lower runs of the chains 13 and 14 are parallel to the upper runs of the chains 2 and 3. The parts are so proportioned and adjusted that directly above 20 each of the vanes 10 on the straight portion of the upper run of the conveyor or carrier, there is a vane 18, the distance between the upper edge of each of the vanes 10 and the corresponding vane 18 being at least as great as the greatest 25 thickness of veneer to be treated in the machine. It is not necessary that the vanes 18 touch the veneer, their purpose being to provide above each of the traveling troughs underneath a piece of veneer a corresponding inverted trough directly 30 above the veneer. Consequently, when warm air is blown into the space between the conveyor and the upper endless member from one side of the machine, in a transverse direction, the air will be divided into a series of separate streams 35 each flowing through its own tunnel or channel and each bounded on the sides by four vanes, two on each side, at the bottom by plates 7 and 8, and at the top by plates 16 and 17. Wherever there are sheets of veneer on the conveyor or 40 lower belt, they divide these tunnels or channels into upper and lower sections; so that the streams of air are again divided, half of each flowing underneath the veneer and the other half across the top. The result is that the veneers lie quietly 45 on the conveyor while it is being carried through the drying chamber, just as though they were not being subjected to strong air currents.

The air enters the right-hand side of the casing or housing, as viewed in Fig. 4, flowing in 50 the direction of the arrow B; the rails 20 and 19 and 6 and 5, together with the lower run of the upper endless belt and the upper run of the conveyor forming upper and lower walls of the air passage through the casing or housing. The 55 air that first strikes the veneers remains in contact therewith across the entire width thereof; and, because it takes up moisture as fast as it can during the first part of its movement, it may be saturated before reaching the far side 60 of the veneer and thus prevent the glue from drying evenly across the width of the veneers. I have found that, if means are provided to produce a turbulence in the air streams from the time they come in contact with the veneers, and thus 65 permit all of the air to be effectively used to absorb moisture, this difficulty can be overcome and the glue be evenly dried. This can conveniently be accomplished by placing in the path of the main air stream, before it is divided, a baffle device 70 extending lengthwise of the casing beside the path of travel of the veneers. In the arrangement shown, the baffle takes the form of an angle iron 22 so located that the two flanges or wings form angles of forty-five degrees with the 75 veneers that are being dried, the plane of the

veneers passing through the apex of the angle in the bar, and this apex pointing away from the veneers. Those strata of the air streams that would otherwise travel straight ahead in contact with the upper and under faces of the veneers are therefore deflected upwardly and downwardly, respectively, before they reach the veneers. By this means a disturbance or turbulence is set up in the air streams so that all parts thereof at one time or another come in contact with the 10 faces of the veneers or, rather, with the glue on those faces.

The warm air or other drying fluid or fluids may be supplied and moved in any suitable way. In the arrangement shown, the fluid is simply 15 re-circulated air; there being enough leakage of air at the ends of the casing or housing to cause the moisture that is taken up from the glue to escape gradually and thus leave the air in the system dry enough to effect its intended purpose. 20 This recirculation of air may conveniently be effected by connecting the air passage through the casing or housing in a closed loop. Thus, the air may enter the drying space or air passage in the casing or housing through a nozzle-like 25 device 24 extending throughout the length of the upper run of the conveyor or carrier and so placed that its upper wall abuts or at least lies close to the upper rail 20, while its lower wall is similarly positioned with respect to the lower 30 rail 6. In other words, the horizontal flanges of the rails 20 and 6 in effect form continuations of the upper and lower walls of the nozzle. This nozzle is connected to and leads from a box-like structure or housing 25 beside the main 35 casing or housing. In this box-like structure are suitable blower devices 26 that discharge into the nozzle. A C-shaped pipe 27 is connected at one end to the box 25, passes across the top of the main casing or housing, and has its outlet end 40 opening into the space between the rails 19 and 5, as best shown in Fig. 4. The cross section of the pipe or conduit 27 may conveniently be that of a rectangle one transverse dimension of which is many times as great as the other. In 45 other words, what may be termed the width of the conduit is preferably about as great as the length of the horizontal portion of the upper run of the carrier, while the other transverse dimension need be only large enough to provide 50 the proper cross-sectional area to permit the efficient re-circulation of the air. Within the pipe or conduit are suitable heat interchangers 28 that warm the air as it passes over them. The heat interchangers may be supplied with steam 55 or other heating fluid that enters through a pipe 29 and leaves through a pipe 30.

The moving elements of the machine may be driven in any suitable way. The blower or blowers can conveniently be driven by a motor 32 60 and the endless belt-like members from a suitable variable speed drive device 33. I have already explained that the two chains of the endless conveyor or carrier run over wheels 9 at the front end of the machine. These wheels are 65 fixed to a transverse shaft 35. At the opposite end of the machine there are wheels 36 similar to the wheels 9. Likewise, the chains of the upper endless belt run over wheels 37 and 38 at the front and rear ends of the machine. The 70 wheels 36 are fixed upon a transverse shaft 39, and the wheels 37 and 38 are fixed to transverse shafts 40 and 41, respectively. On the shafts 40 and 41 are sprocket wheels 42 and 43 over which runs a sprocket chain 44. On the shaft 40 is 75

a pulley 45 and, running over this pulley and a pulley 46 on the variable speed drive, is a belt 47. The upper endless belt is therefore driven directly from the variable speed drive. The shafts 5 41 and 39 have thereon like gear wheels 48, 48 meshing with each other, so that the endless conveyor or carrier is driven directly from the shaft 41 at exactly the same linear speed as the upper endless belt.

10 If desired, the lower run of each of the chains of the endless conveyor or carrier may be supported upon a rail 49 that may be similar to the rails 6 and 5, and the upper run of each of the chains of the upper endless belt may be 15 supported by and run along a rail 50 similar to the rails 19 and 20.

With my improved machine I am able thoroughly to dry glue-sized veneers rapidly and with no other labor than that required to lay 20 the sheets, one at a time, on the endless conveyor at the inlet end of the machine. By supporting the veneers on the narrow edges of thin vanes, I am able not only to distribute the flowing air in such a manner that the veneers are not blown 25 about, but also to dry both sides at the same time, where both faces of the veneer are glue-sized. By drying quickly and making the drying process a continuous one, large quantities of veneers may be dried in a single machine; and, 30 furthermore, along with proper temperature control, the drying of synthetic resin glues can be effected without objectionable change in the "advancement" of the glues.

While I have illustrated and described with 35 particularity only a single preferred form of my invention, I do not desire to be limited to the exact structural details thus illustrated and described; but intend to cover all forms and arrangements which come within the definitions of 40 my invention constituting the appended claims.

I claim:

1. In a machine of the character described, 45 two parallel members located one above the other and spaced a short distance apart, said members being movable in the same direction and at the same speed, each of said members having wide, deep, closely spaced troughs extending transversely across the same on the side toward the other member, and means for causing currents of 50 a drying fluid to flow through said troughs in contact with veneers or the like lying on the lower member.

2. In a machine of the character described, two parallel members located one above the other and 55 spaced a short distance apart to permit veneers or the like to be placed between them, said members being movable in the same direction and at the same speed, each of said members having wide, deep, closely spaced troughs extending 60 transversely across the same on the side toward the other member, the troughs in the upper member being inverted and approximately registering with the troughs in the other member, and means for causing currents of a drying fluid to flow through said troughs above.

3. In a machine of the character described, two parallel members located one above the other and 65 spaced a short distance apart to permit veneers or the like to be placed between them, said members being movable in the same direction and at the same speed, each of said members having wide, deep, closely spaced troughs extending transversely across the same on the side toward the other member, and means for causing 70 turbulent currents of a drying fluid to flow

through said troughs in contact with the veneers or the like.

4. In a machine of the character described, a horizontal, movable carrier having in the top wide, deep troughs arranged close together and 5 extending transversely across the same, means to cause drying fluid to flow through said troughs and across the top of sheets of veneer or the like resting on the carrier, and means above the carrier to cause the flow across the top of the 10 said sheets to be divided into streams similar to and flowing in the same directions as the streams through said troughs.

5. In a machine of the character described, a horizontal, movable carrier having in the top wide, deep troughs arranged close together and 15 extending transversely across the same, means to cause a drying fluid to flow through said troughs beneath sheets of veneer or the like resting on the carrier and also across the tops of 20 such sheets, means above the carrier to cause the flow across the top of the said sheets to be divided into streams similar to and flowing in the same directions as the streams through said troughs, and means to produce turbulence in said 25 streams.

6. In a machine of the character described, two horizontal endless belts arranged one above the other, the upper run of the lower belt being spaced apart from and parallel with the lower 30 run of the upper belt, elements on each belt co-operating with the vanes to form along each of said runs a series of open-ended troughs each closed at three sides and open at the fourth side and at the ends, transverse vanes on and projecting 35 outwardly from each of the belts, the combined height of two vanes, one on each belt, being less than the distance between the aforesaid runs to permit sheets of veneer or the like to be laid on and be supported by the upper edges of 40 the vanes along the upper run of the lower belt, and means for causing a drying fluid to flow crosswise through the space between said runs.

7. In a machine of the character described, two horizontal endless belts arranged one above 45 the other, the upper run of the lower belt being spaced apart from and parallel with the lower run of the upper belt, vanes extending crosswise of each belt and projecting outwardly therefrom at right angles thereto, elements on each belt co-operating with the vanes to form along each of 50 said runs a series of open-ended troughs each closed at three sides and open at the fourth side and at the ends, the vanes on the upper run of the lower belt registering with the corresponding 55 vanes on the lower run of the upper belt but being spaced apart far enough to permit sheets of veneer or the like to be laid on the upper edges of the vanes along the upper run of the lower belt, and means for causing a drying fluid to flow 60 through the space between said runs of the belt in the direction of the length of said vanes.

8. In a machine of the character described, two horizontal endless belts arranged one above the other, the upper run of the lower belt being 65 spaced apart from and parallel with the lower run of the upper belt, elements on each belt co-operating with the vanes to form along each of said runs a series of open-ended troughs each closed at three sides and open at the fourth side 70 and at the ends, vanes extending crosswise of each belt and projecting outwardly therefrom at right angles thereto, the thickness of each vane being only a very small fraction of the distance between consecutive vanes the combined height 75

of two vanes, one on each belt, being less than the distance between the aforesaid runs to permit sheets of veneer or the like to be laid on and be supported by the upper edges of the vanes 5 along the upper run of the lower belt, and means for causing a drying fluid to flow through the space between said runs of the belts in the direction of the length of said vanes.

9. In a machine of the character described, 10 two horizontal endless belts arranged one above the other, the upper run of the lower belt being spaced apart from and parallel with the lower run of the upper belt, elements on each belt co-operating with the vanes to form along each of 15 said runs a series of open-ended troughs each closed at three sides and open at the fourth side and at the ends, transverse vanes on and projecting outwardly from each of the belts, the thickness of each vane being only a very small fraction 20 of the distance between consecutive vanes the combined height of two vanes one on each belt, being less than the distance between the aforesaid runs to permit sheets of veneer or the like to be laid on and be supported by the upper edges 25 of the vanes along the upper run of the lower belt, and means for causing turbulent streams of drying fluid to flow crosswise through the space between said runs.

10. In a machine of the character described, 30 a housing, two endless movable belts extending lengthwise through the housing one above the other, the upper run of the lower belt and the lower run of the upper belt being horizontal and parallel and, in effect, imperforate, conduit 35 means connecting the space between said runs at one side of the housing to the same space at the opposite side of the housing, blower means in said conduit means to cause a circulation of air through said conduit means and said space, and means on said belts to support sheets of 40 veneer or the like about midway between said runs with substantially the entire surface of each exposed and at the same time divide the air flowing through said space into numerous individual 45 streams flowing crosswise of the housing.

11. In a machine of the character described, a 50 housing, two endless movable belts extending lengthwise through the housing one above the other, the upper run of the lower belt and the lower run of the upper belt being horizontal and parallel and, in effect, imperforate, conduit means connecting the space between said runs at

one side of the housing to the same space at the opposite side of the housing, blower means in said conduit means to cause a circulation of air through said conduit means and said space, means to heat said air, and means on said belts to support sheets of veneer or the like about midway between said runs with substantially the entire surface of each exposed and at the same time divide the air flowing through said space into numerous individual streams flowing crosswise of 10 the housing. 5

12. In a machine of the character described, 15 two parallel members located one above the other and spaced a short distance apart to permit wood veneers to be positioned between the same and be supported on the lower member, each of said members being shaped to form with such veneers parallel open-ended tunnels, means for moving said members at the same speed transversely of the direction of length of said tunnels, and means 20 for causing currents of a drying fluid to flow through said tunnels.

13. In a machine of the character described, 25 two parallel members located one above the other and spaced a short distance apart to permit wood veneers to be positioned between the same and be supported on the lower member, each of said members being shaped to form with such veneers parallel open-ended tunnels, means for moving 30 said members at the same speed transversely of the direction of length of said tunnels, means for causing drying fluids to flow through said tunnels, and means to set up a turbulence in such fluids upon entering the tunnels. 35

14. In a machine of the character described, 40 two horizontal endless belts arranged one above the other, the upper run of the lower belt being spaced apart from and parallel with the lower run of the upper belt, transverse vanes on and projecting outwardly from each of the belts, the 45 vanes on each belt forming with the latter a series of open-ended troughs closed on three sides and extending across the belt, the combined height of two vanes, one on each belt, being less than the distance between the aforesaid runs to permit sheets of veneer or the like to be supported by the upper edges of the vanes along the upper run of the lower belt, and means to cause a drying fluid to flow through said troughs both above and below said sheets. 50

CHARLES B. NORRIS.
